HIS ATTORNEY

repeater relay 2LGPR. The operating circuit for signal 2LA, only a portion of which is shown, includes contacts 1WR-38, 1WR-39, 2HR-40, contact 2HR-41 closed in the right-hand position, winding 42 of signal 2LA, and conductor C. Contact 53 of relay 2LGPR will therefore complete a second circuit for energizing relay 2HF, this circuit passing from terminal B, through contact 2LGPR-53, contact 54 of relay 2HR in the right-hand position, front point of contact 55 of relay 2HR, and the winding of relay 2HF to conductor C.

It follows that with the apparatus as shown in Fig. 1, signal indication lamp 2K will first become lighted on account of the energization of relay 2HCR when the circuit for relay 2HR is closed, and may then be extinguished during the interval of time between the opening of contact 51 of relay 2HF, on account of relay 2HR opening contact 55 at the back point, and the subsequent closing of contact 51 of relay 2HF when contact 2LGPR-53 completes the second circuit traced for relay 2HF. If, for some reason, signal 2LA should not at once clear, contact 55 of relay 2HR would open at its front point, and would then complete, at its back point, the circuit first traced for relay 2HF. Relay 2HF would thus be periodically energized and deenergized until signal 2LA cleared, or until the leverman moved lever 2V away from the r position. Signal indication lamp 2K would thus display a flashing indication.

I shall now assume that with the apparatus modified as shown in Fig. 2, the leverman desires to clear signal 2LA. He will therefore move lever 2V to its r position, causing relay 2HR to become energized by current of reverse polarity passing from battery 2Q, through conductor C, winding of relay 2HR, contact 31 of relay 2HF, conductor 30, winding of relay 2HCR, and contact 29 of lever 2V in the right-hand position to terminal N. With relay 2HR energized by current of reverse polarity, a circuit will be completed for periodically energizing relay 2HF by current passing from terminal B, through contact 32 of coder D, contact 2LGPR-34, contact 35 of relay 2HR closed in the right-hand position, contact 36 of relay 2HR, and the winding of relay 2HF to conductor C. Relay 2HF, being periodically energized, will periodically open its contact 31 in the circuit previously traced for relays 2HCR and 2HR, causing contact 31 of relay 2HCR to be periodically opened. Lamp 2K will therefore display a flashing indication until signal 2LA clears and causes contact 2LGPR-34 to open.

Upon the operation of signal 2LA to its G or Y position, selected in accordance with traffic conditions in advance, contact 22 or contact 23, respectively, of signal 2LA will open, causing relay 2LGPR to become deenergized. With relay 2LGPR deenergized, contact 2LGPR-34, operated by this relay, will open the circuit previously traced for relay 2HF, and hence contact 31 of relay 2HF will be constantly closed, causing relay 2HCR to be constantly energized, which in turn causes lamp 2K to be constantly energized.

From the foregoing description and the accompanying drawing, it follows that in apparatus embodying my invention, operations of a track switch may be governed by switch control circuits including a switch control conductor and a common conductor, and signal control circuits including a signal control conductor and the same common conductor as is used in the switch control circuits, govern the clearing of one or

more signals. A signal indication device is controlled by indication circuits which include the signal control conductor and the common conductor. In one form of apparatus embodying my invention, there may be a single interruption of the signal indication device when a signal is being cleared in normal operation. If, however, a signal should fail to clear properly, there would be repeated interruptions of the signal indication device. The signal indication device is operated constantly as soon as the signal corresponds to the condition of energization of the signal control relay. In a second form of apparatus embodying my invention, the signal indication device is periodically operated from the time the signal control relay is energized until the signal corresponds to the condition of energization of the signal control relay.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, an electrically controllable device, a control relay, means including a front contact of said control relay for effecting operation of said electrically controllable device, an indication relay, a circuit controlled by a back contact of said control relay for energizing said indication relay, a second circuit for energizing said indication relay closed when said electrically controllable device responds to energization of said control relay, a second indication relay, a manually controllable circuit including the windings of said control relay and of said second indication relay as well as a front contact of said first indication relay and a source of current, and indication means controlled by said second indication relay.

2. In combination, an electrically controllable device, a control relay, means controlled by said control relay when energized for operating said electrically controllable device, an indication relay, a circuit controlled by a back contact of said control relay for energizing said indication relay, a second circuit for energizing said indication relay controlled by a front contact of said control relay and closed when said electrically controllable device responds to energization of said control relay, a second indication relay, a manually controllable circuit including the windings of said control relay and of said second indication relay as well as a front contact of said first indication relay and a source of current, and indication means controlled by said second indication relay.

3. In combination, a stretch of railway track, a first and a second signal each operable for governing traffic movements into said stretch, a polarized control relay, means controlled by a front neutral and a normal polar contact of said control relay for operating said first signal, means controlled by a front neutral and a reverse polar contact of said control relay for operating said second signal, an indication relay, means controlled by said control relay when said control relay becomes energized by current of normal polarity for periodically energizing said indication relay until said first signal responds to such energization of said control relay, means controlled by said control relay when said control

- relay becomes energized by current of reverse polarity for periodically energizing said indication relay until said second signal responds to reverse energization of said control relay, manually controllable normal and reverse energizing circuits for said control relay, and indication means controlled over said normal and reverse energizing circuits by said indication relay.
4. In combination, a stretch of railway track, a first and a second signal each operable for governing traffic movements into said stretch, a polarized control relay, means controlled by a front neutral and a normal polar contact of said control relay for operating said first signal, means controlled by a front neutral and a reverse polar contact of said control relay for operating said second signal, an indication relay, means controlled by said control relay when said control relay becomes energized by current of normal polarity for periodically energizing said indication relay until said first signal responds to such energization of said control relay, means controlled by said control relay when said control relay becomes energized by current of reverse polarity for periodically energizing said indication relay until said second signal responds

to reverse energization of said control relay, manually controllable normal and reverse energizing circuits for said control relay, and indication means controlled by said indication relay.

5. In combination, a stretch of railway track, a first and a second signal each operable for governing traffic movements into said stretch, a pair of conductors, manually controllable means controlled over said pair of conductors for effecting operation of said first signal, other manually controllable means controlled over said pair of conductors for effecting operation of said second signal, an indication relay, means controlled by said first manually controllable means when put in condition for effecting operation of said first signal to periodically energize said indication relay until said first signal becomes operated, means controlled by said other manually controllable means when put in condition for effecting operation of said second signal to periodically energize said indication relay until said second signal becomes operated, and indication means controlled over said pair of conductors by said indication relay.

JOHN M. PELIKAN.

UNITED STATES PATENT OFFICE

2,216,626

RAILWAY TRAFFIC CONTROLLING
APPARATUS

John M. Pelikan, Pittsburgh, Pa., assignor to The Union Switch & Signal Company, Swissvale, Pa., a corporation of Pennsylvania

Original application March 20, 1937, Serial No. 132,067. Divided and this application June 9, 1939, Serial No. 278,311

5 Claims. (Cl. 246—219)

My invention relates to railway traffic controlling apparatus of the type involving switches and signals controlled by manually operable means, such for example as levers located at a control point, and has for an object the provision of means for accomplishing the control and indication for signals with a minimum number of line wires between the control point and the controlled device.

10 The present application is a division of my co-pending application, Serial No. 132,067, filed March 20, 1937, for Railway traffic controlling apparatus.

15 I shall describe several forms of apparatus embodying my invention, and shall then point out the novel features thereof in claims.

20 In the accompanying drawing, Fig. 1 is a diagrammatic view showing one form of apparatus embodying my invention for controlling and indicating one or more signals over a pair of conductors comprising a signal control conductor and a common conductor. Fig. 2 is a diagrammatic view showing a modification of the control and indication circuits shown in Fig. 1.

25 Similar reference characters refer to similar parts in each of the views.

Referring first to Fig. 1, the reference characters 3 and 3a designate the track rails of a track section E—F which is separated by means 30 of insulated joints 4 from adjacent portions of a stretch of railway track. Track section E—F is provided with a track circuit including a battery 5 connected across the rails adjacent one end of the section, and a track relay TR connected across the rails adjacent the opposite end 35 of the section.

Located in section E—F, is a track switch 1. This switch is operated by a mechanism M which is controlled by a slow release polarized switch control relay 1WR.

40 Adjacent the point E, signals 2RA and 2RB are located for governing traffic movements over switch 1 from left to right as shown in the drawing, which I shall assume is the eastbound direction. Signal 2LA, adjacent point F, is for governing westbound traffic movements over switch 1 in the normal position in which it is shown in the drawing. The signals are controlled in part by a slow release polarized signal control relay 2HR.

45 In each of the views, the contacts operated by the various relays or other devices are identified by numbers, such numbers having distinguishing prefixes from which they are separated by a dash when the contacts are shown apart from the relay 50 or other device by which they are operated. The

prefix for each of these contact numbers comprises the reference character for the respective relay or other device. For example, contact 1WR—12, shown in the operating circuits for switch mechanism M, is identified by the number 5 12 separated by a dash from the prefix 1WR which is the reference character for relay 1WR by which this contact is operated. Similarly, contact 2HR—41, shown in the operating circuits for signals 2RA and 2LA, is identified by the 10 number 41 separated by a dash from the prefix 2HR which is the reference character for relay 2HR by which this contact is operated.

Switch control relay 1WR and signal control relay 2HR are manually controllable by devices, 15 such for example as levers 1V and 2V, respectively, located at a control point which may be an interlocking tower or dispatcher's office. Each of these levers has a normal position n, in which it is shown in the drawing, and a reverse 20 position r to the right. Lever 2V has also a reverse position f to the left.

The normal and reverse energizing circuits for relay 1WR include a switch control conductor 9 and a common conductor C. The normal and reverse energizing circuits for relay 2HR include a signal control conductor 30 and the common conductor C.

The circuits for relays 1WR and 2HR are supplied with current for energizing these relays 30 from a suitable source, such for example as batteries 1Q and 2Q located at the control point. The positive terminal of battery 2Q and the negative terminal of battery 1Q are connected together and with common conductor C. Battery 35 1Q has a positive terminal B, and battery 2Q has a negative terminal N.

The switch control circuits for energizing relay 1WR include a contact 10 of a lock relay 1LR. Relay 1LR may be controlled by track relay TR 40 and by an approach locking relay, or by any other means desired. The approach locking relay for controlling relay 1LR may be controlled in any suitable manner, such for example as shown for relay L in Letters Patent of the United States, No. 45 1,956,851, granted May 1, 1934 to C. A. Brooks and J. M. Pelikan for Railway traffic controlling apparatus.

A signal indication relay 2HF, as here shown, is of a slow release type. Relay 2HF is energized by 50 current from terminal B of battery 1Q. Two circuits for energizing relay 2HF are controlled by signal repeater relays 2LGPR and 2RGPR, respectively, in conjunction with a front neutral contact and a polar contact of relay 2HR. A 55

third circuit is provided for relay 2HF, controlled by a back contact of relay 2HR.

The signal control circuits for energizing relay 2HR include the winding of a second signal indication relay 2HKR in series with the winding of relay 2HR, and also include front contact 51 of the first signal indication relay 2HF. A signal indication device, such for example as a lamp 2K, is controlled by the second signal indication relay 2HKR.

As here shown, signals 2RA, 2RB and 2LA are of the searchlight type, but may be of any other suitable design. As shown in the drawing, each of these signals comprises a member 43 mounted to oscillate between two extreme positions, and controlled by a winding 42, and by a permanent magnet or an electromagnet, not shown, so that when winding 42 is energized, member 43 will move to one of its extreme positions or the other, according as winding 42 is energized by current of normal or reverse polarity. Member 43 is biased to a middle position, in which it is shown in the drawing, and which it occupies when winding 42 is deenergized. Member 43 carries three roundels G, R and Y arranged to cooperate with an electric lamp *i* in such manner that when member 43 is in its middle position, roundel R is in front of lamp *i*, whereas when member 43 is swung to the left or to the right, roundel Y or roundel G, respectively, is placed in front of lamp *i*. As shown in the drawing, lamp *i* is above the roundels, but the lamp is placed in this location for purposes of illustration, and it is to be understood that in actual practice the lamp is directly behind the roundels. Each lamp *i* is connected directly with terminals *x* and *o* of a suitable source of current, and is therefore constantly lighted. A signal of this type is disclosed and claimed in Letters Patent of the United States, No. 1,864,224, granted to Wesley B. Wells on June 21, 1932, for Light signals.

Each of the signals operates a contact 22 which is closed when its member 43 occupies the R or Y position, but is open when member 43 occupies the G position. Each of the signals 2RA and 2LA also operates a contact 23 which is closed when its member 43 occupies the R or G position, but is open when member 43 occupies the Y position.

Relay 2LGPR is controlled by signal 2LA, and is energized only when signal 2LA is indicating stop. Relay 2RGPR is similarly controlled by signals 2RA and 2RB.

As shown in Fig. 2, periodically interrupted current is provided by passing current from terminal B through contact 32 of a coding device D. Coding device D may be of an oscillatory type operating at a low frequency of the order of 120 cycles per minute, and provided with a self-control contact 6 as well as with contact 32 for periodically interrupting the current supplied from terminal B, and also having a winding designated by the numeral 120 corresponding to the frequency of operation of coding device D. The contacts of coder D are biased by a coil spring 7 to the position shown in the drawing, when the coder is deenergized. Coder D is connected directly with conductor C and, through its contact 6, is connected with terminal B, and is therefore constantly in operation.

In Fig. 2, signal indication relay 2HF, instead of being of the slow release type as shown in Fig. 1, is quick enough acting to respond to the periodically interrupted current supplied from contact 32 of coder D to circuits controlled by signal control relay 2HR and by signal repeater relays

2RGPR and 2LGPR. Relay 2HR is here controlled by a back contact 31 of relay 2HF instead of by a front contact as in Fig. 1.

Having described, in general, each of the forms of apparatus shown embodying my invention, I shall now trace in detail the operation of these forms of apparatus.

As shown in the drawing, all parts are in the normal condition, that is, the switch and signal control levers 1V and 2V, respectively, are in their normal position *n*; switch 1 is in its normal position; signals 2RA, 2RB and 2LA are indicating stop; coding device D is operating; relays TR, 2RGPR, 2LGPR, 1WR and 1LR are energized; relay 2HF of Fig. 1 is also energized; relays 2HR and 2HKR of both figures, and relay 2HF of Fig. 2 are deenergized; lamps *i* of signals 2RA, 2RB and 2LA are lighted, and signal indication lamp 2K is unlighted.

I shall first trace the operation of the form of apparatus shown in Fig. 1.

With switch control lever 1V in its *n* position, switch control relay 1WR is energized by current of normal polarity passing from terminal B, through contact 8 of lever 1V in the left-hand position, switch control conductor 9, contact 10 of relay 1LR, and the winding of relay 1WR to common conductor C. With relay 1WR thus energized by current of normal polarity, the normal operating circuit for switch mechanism M is arranged, passing from terminal B, through contact 1WR-12, contact 1WR-13 closed in the left-hand position, mechanism M, and contact 1WR-14 closed in the left-hand position to conductor C.

With signals 2RA and 2RB indicating stop, signal repeater relay 2RGPR is energized by its circuit passing from terminal B, through contacts 22 and 23 of signal 2RA, contact 22 of signal 2RB, and the winding of relay 2RGPR to conductor C. With signal 2LA indicating stop, signal repeater relay 2LGPR is also energized by its circuit passing from terminal B, through contacts 22 and 23 of signal 2LA, and the winding of relay 2LGPR to conductor C.

With relay 2HR deenergized, relay 2HF is energized by its circuit passing from terminal B, through the back point of contact 55 of relay 2HR, and the winding of relay 2HF to conductor C.

I shall assume that, with switch 1 in its normal position, the leverman desires to clear signal 2LA. He will therefore move lever 2V to its *r* position, causing relay 2HR to become energized by current of reverse polarity passing from battery 2Q, through conductor C, winding of relay 2HR, contact 51 of relay 2HF, conductor 30, winding of relay 2HKR, and contact 29 of lever 2V in its right-hand position to terminal N. Completion of this circuit causes relay 2HKR to close its contact 37, thereby completing a circuit passing from terminal B, through contact 37, for lighting signal indication lamp 2K.

Relay 2HR, upon becoming energized, opens its contact 55 at the back point, deenergizing relay 2HF, and then closes this contact at the front point, and closes its polar contacts in the reverse position. Upon the lapse of a brief period of time required because relay 2HF is slow releasing, contact 51 of relay 2HF may open the circuit traced for relay 2HR. Since relay 2HR is also slow releasing, the front contact of this relay will not open immediately. Before the front contact of relay 2HR has had time to open, signal 2LA will have cleared and opened the circuit for signal 75.
